HANDLE FOR HUNTING KNIFE

Rudolf Koppe, 27 Kenninghall Blvd.,
Streetsville, Ontario, Canada

Filed Dec. 14, 1972, Ser. No. 315,128

Term of patent 14 years

Int. Cl. D22—02; D8—03

U.S. Cl. D22—1

FIG. 1

FIG. 3

FIG. 5

FIG. 2

FIG. 4

FIG. 1 is a slightly enlarged perspective view as compared with FIGS. 2, 3 and 4 of the drawings, of the handle for hunting knife taken from a point forwardly of to the right and above the forward section of the handle.

FIG. 2 is a side elevational view of the handle of FIG. 1 showing the outline of the side opposite to that illustrated in FIG. 1.

FIG. 3 is a top plan view of the handle illustrated in FIG. 2.

FIG. 4 is a bottom plan view of the handle illustrated in FIG. 2, and

FIG. 5 is a rear elevational view of the handle of FIG. 2.

The broken line showing of a portion of a blade in FIG. 1 is for illustrative purposes only.

I claim:

The ornamental design for a handle for hunting knife, as shown and described.
